GEORGE A. WARNER, OF DETROIT, MICHIGAN.

BRICKMAKING.

1,420,796.

Specification of Letters Patent. Patented June 27, 1922.

Application filed December 29, 1921. Serial No. 525,591.

To all whom it may concern:

Be it known that I, GEORGE A. WARNER, a citizen of the United States, residing at Detroit, in the county of Wayne and State 5 of Michigan, have invented certain new and useful Improvements in Brickmaking, of which the following is a specification.

This invention relates to the manufacture of bricks and other similar articles molded 10 from clay or similar material. It has for its object both the process and the apparatus for manufacturing the bricks or similar articles.

Bricks are now ordinarily molded in a 15 brick machine. This brick machine is simply a machine provided with a suitable feed for the wet clay and a powerful ram for compressing the clay and a die at the bottom of the ram through which the wet 20 clay is forced into a mold on the table of the machine. This mold is simply a wooden box with a plurality of compartments to form the bricks. After the ram has descended and started on its up stroke the machine 25 ejects the mold box and another one is placed therein. In ejecting the mold box at the front of the machine the bottom of the die passes over the mold box to scrape off the top surfaces of the preliminary formed 30 bricks to make a clean upper surface.

However, in actual practice it is found that after the plastic material has stood but a short time the level of each preliminary formed brick alters and the same 35 begins to swell at the top and center. This is due to the fact that the clay is moist and is forced into the compartments of the mold box under tremendous pressure. As soon as the pressure is released the material starts 40 to swell out, hence it is usually required to level off these mold boxes again before the material is dumped out onto the pallet.

It is the object of the present invention to neutralize this swelling action by cutting 45 a shallow groove or corrugation in the top of the preliminary formed brick as it issues from the machine. Now obviously this process is largely useful in connection with bricks made by machine but obviously hand- 50 stamped molds present the same problem in a lesser measure and the process is equally applicable to them.

In the drawings,—

Fig. 1 is a fragmentary view of a part of 55 a brick machine showing the ram, the die at

the bottom of the machine, and the mold box on the table.

Fig. 2 is a perspective of the die.

Fig. 3 is a perspective of the mold box.

a designates the outside shell of the machine; *b* the ram, and *c* the die at the bottom of the compression chamber. This is provided with a plurality of clay cutting bars or guides *e* which have their edge portions directed upwardly and divide the mass of clay as it is forced down by the ram and so that a plurality of separate streams of clay under pressure flow into the mold compartments. Now ordinarily the front lower edges of this die are straight, as is also the 70 case with the mold box designated *f*. These edges of the die become scrapers to clean off the top of the mold box when this is ejected from the front of the machine onto the table.

In place of making this surface straight 75 I make the surface of the die both at the front and the rear with corrugations *g*. In short, the entire under surface of the die is fluted, the corrugations being adjacent the cutting bars and the convexities opposite 80 the openings between the cutting bars. Conversely on the upper edges of the mold box the fluting is such that the corrugations are opposite the openings in the mold box and the convexities are opposite the partitions, as 85 will clearly appear from Fig. 3. Hence when the mold box is ejected from the die a slight shallow groove is made in the upper surface of the preliminarily formed brick. This compensates for the succeeding swelling 90 of the brick and is nicely calculated to effect a substantially accurate compensation for the swelling. I find that with an ordinary 2 x 4 x 8" brick that a corrugation having a maximum depth of about $\frac{3}{16}$ of an 95 inch is about right to accomplish the purpose. Of course, no exact dimensions can be maintained because the amount of grooving of the top of the brick will have to depend largely upon the amount of pressure used 100 and also upon the character of the material that goes to form the brick.

The top of the brick in the mold becomes the bottom of the brick on the pallet. Therefore, if it is so desired, the groove in 105 the plastic brick may be made deeper and greater than is necessary to compensate for the swelling. This will give a certain hollow in the brick when laid on the pallet which will give a space for the material to 110

spread to the inside when the pressure of the soft plastic material causes it to spread slightly at the bottom, as is now the case with ordinarily formed bricks.

5. What I claim is:

1. In a molding apparatus for forming bricks or similar articles, the combination of a mold box provided with a plurality of compartments and having side walls that are corrugated or fluted, and a member having matching corrugations or flutings that can be passed over the mold box to corrugate the plastic bricks, for the purpose specified.
15. 2. In a molding apparatus for forming bricks or similar articles, the combination of a mold box provided with a plurality of partitions forming compartments and side walls provided with flutings in which the concavities are adjacent the compartments and the convexities adjacent the partitions, and a member for passing over the mold box and having matching fluting on the side walls.
25. 3. In a molding apparatus for forming bricks or similar articles, a mold box provided with a compartment to mold a brick, the side of the mold box being provided with a shallow corrugation, and a member provided with a matching convexity that can be passed over the mold box as a scraper to provide a shallow corrugation in the top of the plastic brick.

4. In a molding apparatus for forming bricks or similar articles, the combination 35 of a die provided with side walls having flutings and a mold box for engaging below the die provided with side walls having a fluting matching with the fluting of the die, the corrugations being opposite the compartments of the mold box whereby when the mold box is ejected from the die the die acts as a scraper to cut shallow corrugations in the tops of the plastic bricks.

5. In a molding apparatus for forming 45 bricks or similar articles, the combination of a die provided with a plurality of side bars having fluting on their lower sides and cutting bars connecting the side bars, the concavities of the fluting being opposite the cutting bars and the convexities opposite the openings between the cutting bars, and a mold box provided with a plurality of partitions connecting two side bars, each of which side bars has its lower edge fluted 50 with the concavities opposite the compartments and the convexities opposite the partitions, said flutings of the die and the mold box matching whereby when the mold box is ejected sidewise from the die shallow 55 corrugations are cut in the tops of the plastic bricks.

In testimony whereof I affix my signature.

GEORGE A. WARNER.
